United States Patent Office

Des. 229,687
Patented Dec. 25, 1973

229,687

TRACTOR CAB

John H. Babbitt, Jr., and Ronald G. Boyer, Peoria, Arthur E. Olt, Jr., Perkin, Paul E. Schuck, Canton, and Sheldon L. Stark, Eureka, Ill., assignors to Caterpillar Tractor Co., Peoria, Ill.

Filed Oct. 2, 1972, Ser. No. 294,233

Term of patent 14 years

Int. Cl. D12—09

U.S. Cl. D14—27 B

FIG -1-

FIG-2-

FIG. 3-FIG. 1 is an isometric view taken from above and to the right front of the tractor cab embodying our new design;

FIG. 2 is an isometric view taken from above and to the left rear of the tractor cab embodying our new design; and

FIG. 3 is an isometric view of a tractor cab showing a second embodiment of our new design; the sole difference being in the addition of an air conditioner unit.

We claim:

The ornamental design for a tractor cab, substantially as shown and described.
